(57) **CLAIM**

The ornamental design for pick for a stringed instrument, as shown and described.

DESCRIPTION

FIG. 1 is a front prospective view of the pick for a stringed instrument of this invention;

FIG. 2 is a top, plan view thereof;

FIG. 3 is a bottom plan view thereof;

FIG. 4 is a back elevational view thereof; and,

FIG. 5 is a left side elevational view thereof.

The right side elevational view is identical to the left side elevational view.
